(57) **CLAIM**

The ornamental design for a jump starter, as shown and described.

DESCRIPTION

FIG. 1 is a front view of a jump starter showing the new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a front, top, and right side perspective view thereof. The broken lines shown in the drawings are for the purpose of illustrating portions of the jump starter that form no part of the claimed design.

The shade lines in the Figures show contour and not surface ornamentation.

1 Claim, 7 Drawing Sheets
